UNITED STATES PATENT OFFICE

2,479,575

LASTING MACHINE

Bernhardt Jorgensen, Marblehead, Mass., assignor to United Shoe Machinery Corporation, Flemington, N. J., a corporation of New Jersey

Application April 1, 1948, Serial No. 18,449

16 Claims. (Cl. 12—12.4)

1

This invention relates to lasting machines and is herein shown as applied to a toe-lasting machine of the same general character as disclosed in United States Letters Patent No. 2,324,509, granted on July 20, 1943 on an application of mine, but modified in some respects as shown in later disclosures including that of Letters Patent No. 2,354,685, granted on August 1, 1944, on another application of mine. It is to be understood, however, that the invention is not limited to machines constructed as shown in the above-mentioned Letters Patent and that in some aspects also it is not limited to the lasting of the toe ends of shoes.

In a machine such as that to which the invention is herein shown as applied a last having an upper and an insole thereon is positioned bottom upward, and while it is held in that position the margin of the upper about its toe end is wiped inwardly over the insole by toe-embracing wipers. The wipers are moved upwardly by a wiper support into positions thus to operate on the upper, the wiper support having also thereon means for wiping the upper heightwise of the last by its upward movement. The wiper support is thus operated by fluid-pressure means comprising a pair of pistons moved upwardly by fluid admitted beneath them from a manifold in which the fluid is maintained under pressure by a continuously running pump. The upward movements of the pistons have served heretofore to compress a pair of springs which, upon release of the fluid under the pistons after the wipers have wiped the margin of the upper inwardly over the insole, act on the wiper support to increase the downward pressure of the wipers on the margin of the upper. At a time in the operation of the machine when the wipers are in their upraised positions, before they wipe the upper inwardly over the insole, the margin of the upper spread outwardly over them is operated upon by upper-trimming means to remove therefrom all but the outer layer of the upper materials, the upper-trimming means also being operated by fluid under pressure from the manifold.

The construction above described has been used heretofore with highly satisfactory results. It will be evident, however, that at the time of the upper-trimming operation the wipers are held upraised by the fluid-pressure means not only against the force of gravity but also against the resistance of the above-mentioned springs which are fairly heavy in order to cause the wipers later to press the margin of the upper on the insole with the required force. To afford

2

better insurance, therefore, that under some conditions a slight momentary drop in the pressure of the fluid in the manifold by reason of the admission of fluid to operate the upper-trimming means will not prevent the wipers from being held upraised firmly enough to support the margin of the upper properly in the upper-trimming operation, the present invention, in one aspect, provides novel means whereby the pressure of the wipers on the margin of the upper over the insole is increased by the action of the operating fluid instead of by springs such as used heretofore. In the construction shown the pistons through which the wiper support is raised as above described are double-acting pistons, and when the pressure is terminated beneath them after the wiping of the margin of the upper inwardly over the insole the pressure is applied above them to force the wipers downwardly. Since it is desirable that provision be afforded for varying the pressure thus applied by the wipers to the margin of the upper, the construction shown further includes a comparatively light spring which supplements the force of the operating fluid on the wiper support in pressing the margin of the upper on the insole, together with means adjustable to vary the stress of this spring. The spring thus provided is arranged to be subjected to stress only near the end of the upward movement of the wiper support and, as compared with the above-mentioned springs used heretofore, exerts but little force in opposition to that of the operating fluid whereby the wipers are held in their upraised positions in the upper-trimming operation.

As disclosed in the above-mentioned Letters Patent No. 2,354,685, the construction provided heretofore has been further such that after the wiper support has been moved upwardly to carry the wipers into positions for wiping the margin of the upper inwardly over the insole, it may be moved still farther upwardly against the force of gravity in response to pressure of the margin of the upper on the wipers as they wipe it inwardly, thus permitting the wipers to be so positioned as to act on the upper with the best results at the extreme edge of the shoe bottom without thereafter acting too severely thereon farther inwardly from the edge, especially if the bottom of the toe end of the last has a convex curvature. To permit such further upward movement of the wiper support, pin-and-slot connections have been provided heretofore between it and the pistons which raise it; and further to prevent the wipers from acting too se-

verely on the margin of the upper the weight of the wiper support and of the parts thereon has been partially counter-balanced by springs carried by the pistons. The present invention further provides, instead of such springs, fluid-pressure means for partially counterbalancing the weight of the wiper support and of the parts thereon, the construction shown comprising comparatively small pistons movably mounted in the pistons which raise the wiper support and subject to the pressure of the operating fluid in the lower ends of cylinders in which the last-mentioned pistons are mounted. It will be evident that in addition to their counterbalancing action the small pistons assist in the raising of the wiper support prior to the operation of the wipers on the upper.

The novel features of the invention, including various novel details of construction and combinations of parts, will now be more particularly described with reference to the accompanying drawings and thereafter pointed out in the claims.

In the drawings,

Fig. 1 is a view mainly in front elevation of a portion of the machine to which the invention is herein shown as applied, with parts broken away;

Fig. 2 is a view mainly in right-hand side elevation, with parts broken away, of a portion of the structure shown in Fig. 1, the parts being shown in the positions which they occupy when the wipers are at the limits of their inward movements over the shoe bottom but before their downward pressure on the margin of the upper is increased; and

Fig. 3 is a view similar to Fig. 2 of a portion of the structure, but with the parts in their initial positions as in Fig. 1.

In view of the prior disclosures, only as much of the machine will be herein described in detail as is necessary for an understanding of the invention. The shoe is positioned heightwise in the machine, bottom upward, by a shoe rest 2 engaging the bottom face of the forepart of the insole substantially as shown and described in Letters Patent No. 2,391,461, granted on December 25, 1945 on an application of mine, except that a spur therein shown for engaging the insole in an indentation formed therein is omitted. The shoe rest 2 is supported by a member 4 which is vertically adjustable on the frame of the machine, and by means of a screw 6 the shoe rest is adjustable relatively to the member 4 about an axis extending widthwise of the shoe, as further disclosed in the last-mentioned Letters Patent. The shoe is clamped against the shoe rest 2 by upward movements of a toe rest 8 and an instep support 10 which, as well as the other operating instrumentalities of the machine, are operated by fluid under pressure from a manifold (not shown) in which the fluid, preferably light oil, is maintained under pressure by a continuously running pump, as disclosed in Letters Patent No. 2,324,509.

At a predetermined time in the operation of the machine the margin of the outer layer of the toe-end portion of the upper materials is wiped inwardly over the insole by a pair of toe-embracing wipers 12. These wipers and their operating means are carried upwardly and downwardly in the course of the operation of the machine by a wiper support 14 which, as fully disclosed in the last-mentioned Letters Patent, is mounted on upper and lower pairs of parallel

links 16 and 18, only one link of each pair being visible in the drawings. Also carried by the wiper support is a toe former 20 which wipes the toe end of the upper heightwise of the last in response to the upward movement of the support, this toe former being herein shown as controlled by mechanism constructed as disclosed in a copending application of mine, Serial No. 759,849, filed on July 9, 1947. The wiper support may thus be moved upwardly twice in the course of the operation of the machine as and for the reasons described in Letters Patent No. 2,337,558, granted on December 28, 1943 on an application of mine. In that case, at the end of its first upward movement the margin of the upper spread outwardly over and supported by the wipers 12 is operated upon by upper-trimming means to remove therefrom all but the outer layer of the upper materials, the upper-trimming means (not herein shown) being operated by fluid from the manifold. At the end of the second upward movement of the wiper support the margin of the outer layer of the upper is wiped inwardly over the insole by the wipers into position to be secured to the insole by cement. The construction may, however, be such that the wiper support is moved upwardly only once, as disclosed in Letters Patent No. 2,324,509, in which case the upper-trimming operation and the wiping of the margin of the outer layer over the insole are both performed at the end of the single upward movement of the support.

In general accordance with the disclosure of Letters Patent No. 2,354,685, the wiper support is moved upwardly by a pair of pistons 22 vertically movable in cylinders 24 which are secured to the frame of the machine and into the lower ends of which fluid is admitted from the manifold through pipes 26. The construction of these pistons and cylinders is different from the earlier construction, as hereinafter explained, and by different means also the upward movements of the pistons are limited to position the wipers in proper relation to the upper-trimming means and to the shoe. The pistons 22 are connected respectively to the opposite side portions of the wiper support 14, as heretofore, by links 28 pivotally mounted on pins 30 in the support and provided at their lower ends with slots 32 through which extend pins 34 mounted in upward extensions of the pistons. During the upward movements of the pistons the pins 34 engage the links at the upper ends of the slots 32 to raise the wiper support. When the wipers are operated to wipe the margin of the upper inwardly over the insole, the slots 32 permit the wiper support and the parts thereon to be moved farther upwardly against the force of gravity in response to pressure of the margin of the upper on the wipers, so that the wipers will not act too severely on portions of the margin of the upper in wiping it inwardly, especially if the bottom of the toe end of the last has a convex curvature.

After the wipers have wiped the margin of the upper inwardly, it is desirable to increase their downward pressure thereon. For this purpose the construction shown in Letters Patent No. 2,354,685 includes a pair of springs arranged to be compressed by the upward movements of the pistons which raise the wiper support and, upon termination of the fluid pressure under the pistons, to cause the wipers thus to apply the increased pressure to the upper. Instead of such springs the present invention provides a construction whereby fluid pressure is utilized

to force the wipers more firmly down on the margin of the upper. For this purpose the upper portions of the pistons 22 are of reduced diameter and are slidingly movable in sleeves 36 which are secured to the upper ends of the cylinders 24 and extend downwardly within the cylinders, the sleeves having thereon upwardly extending lugs 37 which engage the pins 34 to limit downward movements of the pistons. Between each of these sleeves and an annular shoulder 38 on the upper end of the larger portion of the corresponding piston 22 is an annular chamber 40 into which operating fluid is admitted at the proper time from a pipe 42 communicating with the chamber through a passage 44 in the cylinder casting 24, the pipe 42 receiving fluid from the manifold. It will be understood that the admission and exhaust of the fluid to and from the two chambers 40 is controlled by a valve similar to other valves shown in Letters Patent No. 2,324,509 with which the machine is provided, and that when the fluid is admitted to the chambers 40 the lower ends of the cylinders 24 are open to exhaust. Before the wipers are retracted from over the bottom of the shoe the pressure of the fluid is terminated in the chambers 40 and is applied again below the pistons to relieve the pressure of the wipers on the margin of the upper. After the wipers have been retracted the lower ends of the cylinders are again opened to exhaust to cause the wiper support to be lowered by gravity. To limit the upward movement of the wiper support the reduced portions of the pistons 22 have thereon flanges 46 of slightly smaller diameter than the interior of the cylinders 24 for engaging the lower ends of the sleeves 36, as illustrated in Fig. 2. These flanges are located short distances above the shoulders 38 on the pistons 22, so that when the pistons are in their uppermost positions the lower ends of the chambers 40 are opposite the entrances to the passages 44 to receive the operating fluid.

Since it is desirable that provision be afforded for varying the pressure applied by the wipers to the margin of the upper, there is further provided a rod 48 which is pivotally suspended at its upper end on an extension of one of the pins 30 and has thereon a spring 50 supported by a washer 52 and nuts 54 on the lower end of the rod. The rod extends through an opening formed in one arm 56 of a three-armed lever 58 pivotally mounted on a pin 60 on one of the cylinder castings 24. A spring 62 seated in a socket in the frame of the machine engages a second arm 64 of the lever and thereby holds the lever in a position determined adjustably by engagement of a third arm 66 thereof with a screw 68 threaded in the frame. It will be evident that adjustment of this screw determines variably the initial distance between the arm 56 and the upper end of the spring 50. Near the end of the upward movement of the wiper support a washer 70 resting on the upper end of the spring 50 is carried into engagement with the arm 56 and during the remainder of the upward movement of the support the spring is compressed by the action of the arm thereon, the amount of its compression depending upon the adjustment of the lever 58. The force of this spring is therefore added to the pressure of the operating fluid in the chambers 40 in pressing the wipers down on the margin of the upper when the pressure is applied in these chambers and the pressure of the fluid in the lower ends

of the cylinders 24 is terminated, and since the force of the spring may be readily varied as above explained provision is afforded for varying as desired the pressure of the wipers on the margin of the upper. To indicate to the operator what the conditions are with respect to this adjustment, a cylindrical portion of the screw 68 projecting forwardly from the frame has thereon a series of marks 72 one or another of which may register with the front face of the frame. It will be understood that as compared with the springs used heretofore for pressing the wipers down on the margin of the upper, as disclosed in Letters Patent No. 2,364,685, the spring 50 exerts but little force in opposition to the pressure of the operating fluid in the lower ends of the cylinders 24 when the wiper support is held upraised by the fluid at the time of the trimming of the margin of the upper. Any tendency, therefore, for the wiper support to be lowered slightly in response to a momentary reduction of pressure in the manifold when the fluid is admitted to operate the upper-trimming means is minimized. By reason, moreover, of the elimination of the springs used heretofore less power is required to raise the wiper support.

Further to insure that the wipers will not act too severely on the margin of the upper in wiping it inwardly over the insole, at which time provision is afforded for further upward movement of the wiper support 14 against the force of gravity in response to pressure of the upper on the wipers as hereinbefore explained, the invention provides novel means for partially counterbalancing the weight of the support and of the parts thereon. For this purpose small pistons 74 are movably mounted in the pistons 22 with their upper ends in positions for engagement with the lower ends of the links 28, the lower ends of the small pistons being subject to the pressure of the operating fluid in the lower ends of the cylinders 24 when such pressure exists. It will be understood that the pistons 74 are of such small diameter that they are not of themselves effective to raise the wiper support, although they assist the pistons 22 in thus raising it. When the wipers wipe the margin of the upper inwardly over the insole, the action of the small pistons in partially counterbalancing the weight of the wiper support and of the parts thereon reduces the resistance to such further upward movement of the support as may result from the pressure of the margin of the upper on the wipers. To limit downward movements of the pistons 74 when there is no pressure in the lower ends of the cylinders 24 they have on their upper ends flanges 76 arranged to engage the pistons 22.

Having described the invention, what I claim as new and desire to secure by Letters Patent of the United States is:

1. In a lasting machine, wipers for wiping the margin of an upper about an end of a last inwardly over an insole on the last, double-acting fluid-operated means movable in opposite directions successively by the pressure of operating fluid thereon, and mechanism for moving the wipers heightwise of the last into positions for wiping the margin of the upper inwardly over the insole by the movement of said fluid-operated means in one direction and for increasing the pressure of the wipers on the margin of the upper over the insole by movement of said means in the opposite direction.
2. In a lasting machine, wipers for wiping the

margin of an upper about an end of a last inwardly over an insole on the last, a support for said wipers mounted for movements heightwise of the last, and fluid-operated means arranged to be moved in one direction to cause said support to carry the wipers heightwise of the last into positions for wiping the margin of the upper inwardly over the insole and thereafter to be forced in the opposite direction by the pressure of operating fluid thereon to increase through said support the pressure of the wipers on the margin of the upper over the insole.

3. In a lasting machine, wipers for wiping the margin of an upper about an end of a last inwardly over an insole on the last, a support for said wipers mounted for movements in opposite directions heightwise of the last, and a pair of double-acting pistons movable in opposite directions by the pressure of operating fluid thereon for imparting corresponding movements to said support and for thereby positioning the wipers relatively to the last before they wipe the margin of the upper inwardly and thereafter increasing their pressure on the margin of the upper over the insole.

4. In a lasting machine, the combination with means for positioning bottom upward a last having an upper and an insole thereon, of wipers for wiping the margin of the upper about the toe end of the last inwardly over the insole, a support for said wipers mounted for upward and downward movements, and fluid-operated means arranged to be moved upwardly by the pressure of operating fluid thereon to raise said support and thereby to position the wipers relatively to the last before they wipe the margin of the upper inwardly and thereafter to be moved downwardly by pressure of the fluid thereon to increase the pressure of the wipers on the margin of the upper over the insole.

5. In a lasting machine, wipers for wiping the margin of an upper about an end of a last inwardly over an insole on the last, means supporting said wipers for movement heightwise of the last, and fluid-operated means for applying to said wipers in engagement with the margin of the upper over the insole force dependent upon the pressure of the operating fluid and tending to move them heightwise of the last to increase their pressure on the margin of the upper.

6. In a lasting machine, wipers for wiping the margin of an upper about an end of a last inwardly over an insole on the last, a support for said wipers mounted for movement heightwise of the last, and fluid-operated means mounted for movement heightwise of the last by the pressure of operating fluid thereon and arranged to act on said wiper support with force dependent upon the pressure of the operating fluid to increase the pressure of the wipers on the margin of the upper over the insole.

7. In a lasting machine, wipers for wiping the margin of an upper about an end of a last inwardly over an insole on the last, a support for said wipers mounted for movement heightwise of the last, and a pair of fluid-operated pistons connected respectively to the opposite side portions of said support and arranged to act thereon with force dependent upon the pressure of the operating fluid to increase the pressure of the wipers on the margin of the upper over the insole.

8. In a lasting machine, wipers for wiping the margin of an upper about an end of a last inwardly over an insole on the last, means supporting said wipers for movement heightwise of

the last, fluid-operated means for applying to said wipers in engagement with the margin of the upper over the insole force dependent upon the pressure of the operating fluid and tending to move them heightwise of the last to increase their pressure on the margin of the upper, and spring means arranged to act additionally on the wipers to increase their pressure on the margin of the upper, said spring means being adjustable to vary the pressure thus applied by the wipers.

9. In a lasting machine, wipers for wiping the margin of an upper about an end of a last inwardly over an insole on the last, fluid-operated means movable in opposite directions successively by pressure of operating fluid thereon, mechanism for moving the wipers heightwise of the last into positions for wiping the margin of the upper inwardly over the insole by the movement of said fluid-operated means in one direction and for increasing the pressure of the wipers on the margin of the upper over the insole by movement of said means in the opposite direction, a spring arranged to be subjected to stress by the movement of the fluid-operated means in said one direction for thereafter further increasing the pressure of the wipers on the margin of the upper, and means adjustable to vary the stress of said spring and thereby to vary the pressure thus applied by the wipers.

10. In a lasting machine, wipers for wiping the margin of an upper about an end of a last inwardly over an insole on the last, a support for said wipers mounted for movements in opposite directions heightwise of the last, fluid-operated means movable in opposite directions successively by the pressure of operating fluid thereon, mechanism for moving said wiper support to position the wipers relatively to the last by the movement of said fluid-operated means in one direction and for moving said support reversely to increase the pressure of the wipers on the margin of the upper over the insole by movement of said means in the opposite direction, a spring arranged to be compressed by a portion only of the movement of the fluid-operated means in said one direction for thereafter further increasing the pressure of the wipers on the margin of the upper, and means adjustable to vary the compression of said spring and thereby to vary the pressure thus applied by the wipers.

11. In a lasting machine, the combination with means for positioning bottom upward a last having an upper and an insole thereon, of wipers for wiping the margin of the upper about the toe end of the last inwardly over the insole, a support for said wipers mounted for upward and downward movements, fluid-operated means for moving said support upwardly to position the wipers relatively to the last before they wipe the margin of the upper inwardly over the insole and for thereafter forcing the wipers downwardly by the pressure of the operating fluid to increase their pressure on the margin of the upper over the insole, a spring arranged to be moved bodily upward by the upward movement of the wiper support, a member toward which the spring is thus movable, said member being arranged to compress the spring in response to the upward movement of said support near the end of that movement to cause the spring thereafter further to increase the downward pressure of the wipers on the margin of the upper, and means for adjusting said member to vary such compression of the spring.

12. In a lasting machine, the combination with

means for positioning bottom upward a last having an upper and an insole thereon, of wipers for wiping the margin of the upper about an end of the last inwardly over the insole, a support for said wipers, means movable to raise said wiper support to carry the wipers upwardly into positions for thus operating on the upper, the wiper support being arranged to be moved thereafter farther upwardly against the force of gravity relatively to the means for thus raising it in response to pressure of the upper on the wipers as they are moved inwardly over the insole, and means subject to the pressure of operating fluid for partially counterbalancing by the pressure of the fluid the weight of said support and of the parts thereon as the support is thus moved farther upwardly.

13. In a lasting machine, the combination with means for positioning bottom upward a last having an upper and an insole thereon, of wipers for wiping the margin of the upper about an end of the last inwardly over the insole, a support for said wipers, means movable to raise said wiper support to carry the wipers upwardly into positions for thus operating on the upper, connections between said means and the wiper support for thus raising it comprising members relatively movable to permit the wiper support further to be raised against the force of gravity in response to pressure of the upper on the wipers as they are moved inwardly over the insole, and additional means subject to the pressure of operating fluid and arranged to act through said connections partially to counterbalance by the pressure of the fluid the weight of the wiper support and of the parts thereon as the support is thus moved farther upwardly.

14. In a lasting machine, the combination with means for positioning bottom upward a last having an upper and an insole thereon, of wipers for wiping the margin of the upper about an end of the last inwardly over the insole, a support for said wipers, fluid-operated means for raising said wiper support to carry the wipers upwardly into positions for thus operating on the upper, the wiper support being arranged to be moved thereafter farther upwardly against the force of gravity independently of said fluid-operated means in response to pressure of the upper on the wipers as they are moved inwardly over the insole, and additional means subject to the pressure

of the operating fluid for partially counterbalancing by the pressure of the fluid the weight of the wiper support and of the parts thereon as the support is thus moved farther upwardly.

- 5 15. In a lasting machine, the combination with means for positioning bottom upward a last having an upper and an insole thereon, of wipers for wiping the margin of the upper about an end of the last inwardly over the insole, a support for said wipers, a pair of pistons movable by the pressure of operating fluid thereon to raise said wiper support to carry the wipers upwardly into positions for thus operating on the upper, the wiper support being arranged to be moved thereafter farther upward relatively to said pistons against the force of gravity in response to pressure of the upper on the wipers as they are moved inwardly over the insole, and additional pistons movably mounted in said first-named pistons and subject to the pressure of the operating fluid for partially counterbalancing by the pressure of the fluid the weight of the wiper support and of the parts thereon as the support is thus moved farther upward.
- 10 16. In a lasting machine, the combination with means for positioning bottom upward a last having an upper and an insole thereon, of wipers for wiping the margin of the upper about an end of the last inwardly over the insole, a support for said wipers, a pair of pistons movable by the pressure of operating fluid thereon to raise said wiper support to carry the wipers upwardly into positions for thus operating on the upper, connections between said pistons and the wiper support for thus raising it, said connections comprising members movable relatively to the pistons to permit further upward movement of the wiper support against the force of gravity in response to pressure of the upper on the wipers as they are moved inwardly over the insole while the pistons are stationary, and additional pistons movably mounted in said first-named pistons and arranged to act on said members in response to pressure of the operating fluid thereon partially to counterbalance by the pressure of the fluid the weight of the wiper support and of the parts thereon as the support is thus moved farther upward.
